UNIVERSAL CRANE SLING

Clarence J. Koons, Columbia, Pa., and Gerald D. Arch-deacon, Fairborn, Ohio, assignors to the United States of America as represented by the Secretary of the Air Force

Application April 19, 1956, Serial No. 579,414

5 Claims. (Cl. 294—78)

(Granted under Title 35, U. S. Code (1952), sec. 266)

The invention described herein may be manufactured and used by or for the United States Government for governmental purposes without payment to us of any royalty thereon.

The subject invention relates to a crane sling arrangement capable of lifting and displacing loads of varied weight and variable weight distribution. More particularly, subject invention relates to a heavy duty sling which may be adjusted for balanced lifting of loads having different centers of gravity, yet may be securely locked in position for each lifting operation, and easily detached and adjusted for each succeeding lift operation.

The present invention is designed to replace the many different types of slings which were formerly necessary where required to handle and displace load members of different weights and weight distribution. An example of the problem involved presents itself in the cargo loading of aircraft where as many as 35 different types of aircraft must be hoisted and displaced from the dock to the cargo ship, each type of a different weight and each having a different center of gravity thereby requiring a different sling configuration to maintain each aircraft in balance. In the past, the cable type sling has been utilized due to its high strength per unit size; however, it has been found necessary to permanently attach the cable members to the main lift ring, thus requiring availability of a considerable number of slings to balance each different type of load.

A chain type sling, although adjustable, has not been utilized for a number of reasons: In the lifting of heavy aircraft, an extremely bulky, heavy duty chain would be required and consequently, very difficult to manage and adjust; furthermore, it has been dangerous to provide chains that would be adjustable upon the main lifting ring because of their tendency to slip out either when not well secured during the lift operation, or when slack is introduced in the chain after the load is taken off; also, as a result of the comparative low strength per unit weight of chain, a high safety factor is sacrificed in order to permit manageability, thus either presenting considerable danger to those working nearby or requiring constant replacement. An additional deterrent to the use of a universal type sling has been the diversity of attachment fittings provided on the aircraft, thus preventing correlation between the sling attachment and the aircraft attachment.

Slings of the cable type have thus been primarily resorted to, being safer and easier to handle and possessing good lift strength per unit weight, although providing little or no means of adjustment. It is thus a primary object of the present invention to provide a sling which can be made adjustable to conform for lifting to a variety of loads of different centers of gravity, is securely adjustable for each load, and is provided with a universal fastening arrangement for attachment to each load.

It is a further object to provide a heavy duty sling,

2

light weight in relation to the weight to be lifted, yet having a high safety factor.

It is a further object to provide a universal sling which due to its light weight and adjustability may be carried with loading apparatus to perform varied handling operations.

It is another object to provide a universal sling arrangement having detachable load fasteners for attachment with fittings permanently provided on the load.

10 A still further object is to provide a universal sling arrangement which may be securely attached for each lifting operation, further secured against release when unloaded, yet is easily detachable from the load and readily adjustable for each succeeding lifting operation.

15 With the above-mentioned and other objects in view, the invention includes a gather link having a circular ring for suspension from a standard crane hook, a plurality of slots extending downwardly from the ring, and an annular retainer plate mounted upon the inner periphery of the ring.

20 A plurality of pendent, light weight cables is each suspended from a particular slot by means of a chain provided at one end of each cable for insertion in the slots. Each chain can then be adjusted within the slot in relation to the weight distribution of aircraft or load to be displaced, and inclosed against release by the retainer plate.

25 To make the sling adaptable to the various aircraft types and various fittings provided on each aircraft, a U-shaped shackle member is provided in swiveled connection at its free ends to the flange portion of the attachment fittings of the aircraft.

30 A socket assembly is provided at the lower end of the cable-chain having an insert portion for placement of the closed end of the shackle, a latch arrangement being provided on the socket to lock the shackle against release. The invention further includes the novel parts and combination and arrangement of parts as hereinafter particularly described and claimed.

Figure 1 is a perspective view showing the universal sling in attached position on the fuselage of an aircraft;

40 Figure 2 is a detailed plan view of the gather link used for adjustable attachment of the cable-chains;

Figure 3 is a side plan view of Figure 2 taken along the lines 3—3 of Fig. 2;

45 Figure 4 is a detailed sectional view of the socket and shackle assemblies;

Figure 5 is a sectional plan view of the socket assembly shown in Fig. 4 showing the bar in unlatched and latched positions;

Figure 6 shows an elevation of a form of attachment 50 of the sling to an aircraft utilizing a spreader bar;

Figure 7 is a view at right angles to that shown in Fig. 6.

Referring more particularly to the drawings, there is shown in Fig. 1 the universal sling arrangement 1 having a main gather link or lifting ring 2 suspended from a standard crane hook 3 which is attached to a crane or hoist mechanism (not shown). Figs. 2 and 3 illustrate in more detailed form the gather link 2 having an inner circular ring 4 for attachment to the hook 3. Extending outwardly and downwardly from the periphery of the ring 4 are four longitudinal slots 5, the edges of each slot being rounded or beveled and tapering inwardly from the surface of the link 2 to permit safe and rapid insertion of the chains. Mounted on the inner periphery of the ring 4 is an annular, channel-shaped retainer plate 7 which is arched to extend over the greater portion of the inner periphery of the ring with its ends spaced apart at least the width of one of the chain slots. The plate 7 is assembled on the ring for rotative slidable movement thereon by welding the plates 7a and 7b into position on the ring to the plate 7c. In this way, the plate

65 70

is permanently self-locked on the gather link 2, yet may be rotated upon the ring 4 to open and close the slots 5.

Fig. 1 further shows the pendent cable-chain members 8 each provided with a chain length 10 attached by means of a coupling 11 to the upper end of the cable 9. The coupling means 12 provided for the interconnection of each cable-chain and an aircraft 6 to be lifted broadly comprise a socket assembly 13 and shackle members 14, the lower end of each cable-chain member 8 being securely attached by means of a swaging operation within a bore 16 provided within the upper cylindrical or tubular portion 15.

As shown in Figs. 4 and 5, each tubular portion 15 is flared outwardly at its upper end 16a to prevent sharp bending of each cable 9. The socket 13 further includes a lower, enlarged cylindrical portion or thimble 17 integral with the upper portion 15 and joined therewith by means of an outwardly tapered shoulder portion 18. The lower portion 17 is provided with an oblong socket or pocket 19 extending axially the length of the portion 17 and converging at its inner extremity into the bore 16. Positioned on diametrically opposed sides of the lower portion 17 are slotted sections 20 and 21 passing laterally into the lower portions to communicate with opposite sides of the pocket 19. A latch or locking bar 22 is pivotally mounted within the slot 20 at its lower inside corner by means of a pin 23 fixed across the slot. The bar 22 is further provided with a stop or catch 24 to limit movement of the bar 22, the lower edge of the slot 21 acting as a stop for the bar 22 as shown in Fig. 4.

A shackle member 14 is also shown in Figs. 4 and 5 having a U-shaped tongue portion 26 and oval-shaped free end portions 28. The shackle 14 is preferably connected to suitable attachment fittings 30 having a flange 31 or other suitable means for placement between the free end portions 28 and the flange 31 are provided with bores 27 and the bore 32 respectively for insertion of the pin shackle 29 thereby permitting pivotal movement of the shackle 14 on the flange.

Figs. 6 and 7 illustrate the use of the universal sling in which a spacer or spreader bar 35 may be used to spread the cable-chains 8 apart in order to provide clearance between the load to be lifted and the sling.

In operation, each of the links of the chain 9 is marked or indexed to conform with the particular aircraft to be loaded. In this way, when an aircraft or load is to be lifted, each of the chains 9 will be inserted into the slots 5 at the link marking relating to the aircraft in order to maintain the center of gravity of the aircraft directly beneath the gather link 2 thereby balancing the aircraft for loading. The retainer plate 7 is, of course, rotated to an upwardly disposed position on the ring 3 to permit insertion or adjustments of the chains 9. Since the retainer plate 7 encloses the greater portion of the ring periphery, it is necessary to rotate the retainer plate a successive number of times to open all of the slots 5 for the chain insertion. After insertion, the retainer plate is rotated downwardly across the mouth of the openings 5 to enclose the chains 9 within the slots 5.

The shackle member 14 may be easily and rapidly inserted, and locked within each socket assembly 12 by lowering the pocket 19 over the outer, closed end of the tongue 26. The closed end of the tongue, as it is forced upwardly into the pocket, will force the latch bar 22 out of the socket and to a substantially upright position in the slot 20, the bar 22 leaning against the closed end of the tongue, as shown dotted in Fig. 4. After the shackle passes the end of the bar 22, the bar will fall back or may be manually pivoted, within the tongue and into the slot 21. Usually, two forward attachments and two rearward attachments are provided on each aircraft. If necessary, suitable spacing means, such as the spreader bar 35 shown in Figs. 6 and 7 may be combined with the sling

arrangement. Of course, if preferable or necessary, a different number of slots, or different number of cable-chains may be provided without deviating from the principles and advantages of the invention. An added feature is the utilization throughout of a cable member 9 which will tend to tighten rather than loosen each attachment fitting 30 during the lifting operation. This is accomplished merely by providing a cable which will tend to unwrap when a load is applied in the direction of tightening of the related fitting. For instance, where the attachment fittings 30 are provided with right-hand threads, as shown in Fig. 5, the cable strands should have a left-hand, or clockwise, lay, as shown in Fig. 1 so that the tendency will be to unwrap in a counterclockwise direction thereby acting to tighten the fitting upon the aircraft.

Upon lifting the aircraft off the ground, each shackle 14 will be restrained against release by the interpositioned bar 22. During the lifting operation the swiveled shackles 14 will permit shifting of the aircraft without imposing undue binding stress on the cables. The chains will, of course, be secured against any possibility of release from the slots 5, since the hook 3 will prevent any upward shifting or rotation of the plate 7.

Upon conclusion of the lifting operation, the chains will remain in position until manually released by rotating the retainer plate 7 away from each slot. Each chain, if necessary, may then be adjusted for the lifting of another aircraft.

To accommodate the heavier loads required to be lifted, the adjustable chain members, of course, will be comparatively heavy with respect to the cable; however, the chain lengths provided will be just sufficient to provide the necessary different sling configurations. In this way, the adjustability of the chains, and lifting strength of the cable are utilized to maximum advantage.

For purposes of exemplification particular embodiments of the invention have been shown and described according to the best present understanding thereof. However, it will be apparent that many changes and modifications in the arrangement and construction of the parts thereof may be resorted to without departing from the true spirit and scope of the invention.

We claim:

1. A universal sling comprising: a lift ring for suspension from a crane, said ring having a central opening with a plurality of slots extending outwardly from the side of said opening into said ring, and a retainer member movably mounted upon the side of said opening; a plurality of cables each provided with a length of chain at one end, adjustably positioned in each of said slots, said retainer member movable to a predetermined position to retain each chain within one of said slots and movable to successively permit release, removal, and adjustment of said chains; and load fasteners interconnecting the opposite end of each of said cables and the load for lifting by said device.

2. A light weight, universal sling for the lifting and displacement of a plurality of load members by a crane wherein each load varies in weight distribution necessitating a varied sling configuration, said sling comprising: a central support having a circular opening extending transversely therethrough, a plurality of slots extending outwardly from the periphery of said opening, and an annular retainer plate rotatably mounted upon the periphery of said opening to permit opening and closing of said slots; a plurality of pendent, light weight cables each provided with a length of chain at one end, the links of each of said chains selectively inserted in said slots in relation to the weight distribution of the load to be displaced, and retained in said slots against release by said retainer plate; and securing means adapted to attach said cables and said load.

3. A lift ring for adjustable attachment of a plurality

of chains thereto, said lifting ring having a transverse opening to receive a crane hook or the like, a plurality of chain slots spaced along the lower periphery of said opening in radial fashion, the upper end of each slot communicating with said transverse opening to receive a chain link in close fitting relation therein, and a channel shaped annular retainer plate rotatably mounted on the periphery of said opening for slidable disposition over said slots to retain the links within said slots, and slidable away from said slots to release the links therefrom.

4. A lightweight, universal sling for the hoisting of a load member, said sling comprising: a lifting ring having a transverse opening for placement of the lifting ring on a crane hook or the like, a plurality of chain slots notched outwardly from the periphery of said opening, and an annular, retainer plate disposed on the periphery of said opening, said retainer plate being of a length sufficient to simultaneously cover said slots and movable about the periphery of said opening to uncover each of said slots; a plurality of pendent, lightweight cables each provided with a length of chain coupled to one end thereof for insertion into a respective chain slot, said chains retained in said slots against release by said retainer plate; and securing means adapted to attach said cables to the load member.

5. A universal sling for lifting and displacing load members of varied weight distributions, said sling com-

prising: a support member having a central opening to accommodate a crane hook or the like and a plurality of slots extending outwardly from the side of said opening, a plurality of pendent members each including means at one end proportioned for insertion into a respective slot and proportioned for engagement with the sides of each respective slot to connect said pendent members to said support member and means at the opposite end of each pendent member to secure said pendent members to the load to be lifted, said support member having a retainer member for disposition on the side of said opening to inclose said means at said one end of said pendent members to prevent accidental separation of said means from said slots.
